UNITED STATES PATENT OFFICE.

JOHN MARTHALER, OF JERSEY CITY, NEW JERSEY.

CAR-ROOF.

SPECIFICATION forming part of Letters Patent No. 408,731, dated August 13, 1889.

Application filed January 4, 1889. Serial No. 295,426. (No model.)

To all whom it may concern:

Be it known that I, JOHN MARTHALER, of Jersey City, Hudson county, New Jersey, have invented an Improved Car-Roof, of which the 5 following is a specification.

This invention relates to an improved car-roof so constructed that it may be partially opened for the escape of passengers in case of accident.

10 The invention consists in the various features of improvement more fully pointed out in the claim.

In the accompanying drawings, Figure 1 is a top view of the central part of my improved 15 car-roof with portion of the dome broken away. Fig. 2 is a vertical longitudinal central section of the same on line $x-x$, Fig. 1. Fig. 3 is a vertical transverse section on line $y-y$, Fig. 1. Fig. 4 is a bottom view of portion of the roof.

The letter a represents a car-roof provided 20 with a large opening a' , preferably at its center. This opening is surrounded by an upwardly-projecting flange b , having a rabbeted 25 upper edge b' . Upon this edge there sets the rabbeted flange c' of a dome or cover c , which entirely closes opening a' . Between the edges $b' c'$ a washer d should be interposed.

In order to lock the dome or cover c to its 30 seat, I suspend therefrom the two hinged rods

e . These rods project through openings a' into the car, and they should be connected to the roof in such a manner that while securely locking the dome in place they may be readily unfastened in case of accident. For 35 this purpose the lower ends of rods e are bent first horizontally and then downwardly, as shown at $e' e^2$. To the lower face of roof a there is hinged a link f , slotted so as to embrace a staple g , driven into roof a . The link 40 f may be projected over the bent portion e' of rod e , and may then be slipped over staple g , to which it is locked by a pin h . The bent portion e^2 of rod e coming into contact with link f will prevent any automatic disengagement of the catch. 45

To remove the dome c it is only necessary to withdraw pin h , when the dome may be readily lifted off the roof.

What I claim is—

50 The combination of car-roof a , having opening a' and flange b , with the dome c and with the hinged bars e , having bent ends $e' e^2$, and with the hinged link f , staple g , and pin h , substantially as specified.

JOHN MARTHALER.
